UNITED STATES PATENT OFFICE

IRVING BALDINGER, OF BROOKLYN, NEW YORK

TUFTING DEVICE

Application filed May 9, 1929. Serial No. 361,578.

This invention relates to tufting devices. Among the objects of the present invention it is aimed to provide a tufting device for a mattress and preferably for a spring mattress in which a loop of thread or cord is used to tie two opposing portions of the mattress together and in which the knot of the loop can with facility be concealed between two opposing sheets of the mattress.

Among other objects of the present invention it is aimed to provide an improved tufting device consisting of eyelets formed in opposing sheets of a mattress, wire loops operatively associated with such eyelets, and loops of thread or cord operatively connecting the wire loops of opposing sheets of the mattress.

It is still another object of the present invention to provide an improved tufting device which can be made at a minimum cost and be applied with facility by the average unskilled operator.

These and other features, capabilities and advantages of the invention will appear from the subjoined detail description of specific embodiments thereof illustrated in the accompanying drawings in which

Figure 1 is a fragmental section of a mattress equipped with the present invention;

Fig. 2 is an enlarged fragmental portion of the mattress showing the tufting devices connected thereto;

Fig. 3 is a fragmental plan of one of the tufting devices connected in place; and

Fig. 4 is a side elevation of another embodiment of wire loop forming a part of the tufting device.

In the embodiment illustrated, there is shown a mattress having an upper upholstered portion 1 and a lower upholstered portion 2 spaced from one another by the springs 3. The upholstered portion 1 has an outer sheet member 4 and the upholstered portion 2 has an outer sheet member 5, which sheet members are provided with eyelets 6 fastened therein in the usual way. These eyelets have connected thereto wire connectors 7 which have loops 8. The loops 8 are formed to receive the loop 9 of a flexible element such as a thread or cord whereby the opposing sheets

4 and 5 of the upholstered portions 1 and 2 respectively may be connected together.

The eyelets 6, as shown in Fig. 2, preferably have a central opening 10 formed by the cylindrical portion 11, having an elongated flange portion 12 positioned on the outer face of the sheet, for instance the sheet 4 illustrated in Fig. 2, and the flange portion 13 clamped against the inner face of the sheet for instance the sheet 4 illustrated in Fig. 2.

The eyelet, in the present instance, is provided with two diametrically opposed orifices 14 and 15, see Figs. 2 and 3, which are preferably provided in the recesses 16 and 17 respectively which register with one another, see for instance Figs. 2 and 3. In actual use, the sheets 4 and 5 are preferably previously provided with the eyelets 6 and so arranged that they will substantially register with one another.

Through the openings 14 and 15 of each eyelet 6 extend the prongs 18 and 19 of a connector 7 with the loop portion 8 extending through the central opening 10 of the eyelet 6 inwardly of the sheet member to which the eyelet is connected. The loop of thread or cord passes through the loops 8, 8, of opposing connectors 7 and are tied together as indicated in Fig. 1 by any suitable means such as the knot 20.

In actual use, the user causes a loop of thread or cord 9 to pass through the loop 8 of the connector 7 extending through an eyelet 6 in the lower sheet 5, and brings the two threads upwardly through the eyelet 6 in the upper sheet 4, there ties a knot 20 in the loop 9 and passes a connector 7 through such loop 9 so that it will extend through the loop 8 and then passes the prongs 18 and 19 through the openings 14 and 15 of the eyelet. The opposing upholstered portions 1 and 2 of the mattress are generally pressed in when the loop 9 of the thread is passed through the eyelet 6 in the upper sheet 4, and consequently when the same is released, the outward tension of the two upholstered portions 1 and 2 will cause the thread quickly to seek its position with the knot 20 concealed between the sheets 4 and 5 respectively. In Fig. 2, the upper sheet 4 is shown broken away and pro-

vided with two eyelets and its wire loops, the eyelet to the left being shown at right angles to the eyelet at the right, although it is obvious that these eyelets may have all of their recesses 16 and 17 in alignment with one another in the upper sheet 4 and likewise in alignment with one another in the lower sheet 5.

Preferably the connector 7 may also be provided with the nicks or depressions 21 and 22 in the prongs 18 and 19 which will cooperate with the eyelet 6 of the orifices 14 and 15 to anchor the connector 7 against accidental displacement, see Fig. 4.

From the foregoing it will be seen that the loops 9 will only engage rounded surfaces, for instance the rounded surface of the wire connector 7, and thus not be subjected to any abrasive wearing action during the use of the mattress, which is of course conducive to the long life of these connecting threads or cords. It will also be seen that the formation of the connector 7 is made out of pieces of wire, serving to decrease the cost of production of these connectors to a minimum.

It is obvious that various changes and modifications may be made to the details of construction without departing from the general spirit of the invention as set forth in the appended claims.

I claim:

1. In a device of the character described, the combination with the opposing sheets of a mattress, of eyelets secured to said sheets, the eyelets in the opposing sheets being arranged in registering pairs, there being orifices in said eyelets, wire connectors, each wire connector having a pair of prongs and an intermediate loop, the prongs of each wire connector extending into the orifices of an eyelet with the intermediate loop extending through the center of the eyelet inwardly of the mattress sheet, and cords formed into loops, each cord connecting the intermediate loops of the wire connectors of a pair of eyelets.

2. In a device of the character described, the combination with the two sheets of a mattress, of eyelets secured to said sheets, the eyelets in such opposing sheets being arranged in pairs, there being a pair of aligned recesses in each eyelet, there being an orifice in the bottom of each recess, a wire connector having a pair of prongs and an intermediate loop for each eyelet, the prongs of each connector extending through the pair of orifices in an eyelet with the intermediate loop extending inwardly through the central opening of the eyelet, and a loop composed of a cord connecting the intermediate loops of the connectors of each pair of registering eyelets.

3. In a device of the character described, the combination with the two outer sheets of a mattress, of a plurality of eyelets se-

cured to said sheets, the eyelets in the opposing sheets being arranged in registering pairs, there being a pair of orifices in each eyelet, a wire connector having a pair of prongs and an intermediate loop for each eyelet, the prongs of each connector extending through the pair of orifices of an eyelet and the intermediate loop extending inwardly through the central opening of the eyelet, each prong having a depression adjacent its free end to cooperate with the eyelet to form an anchoring means, and a loop of cord or the like connecting the intermediate loops of the wire connectors of each pair of eyelets.

4. Fastening means for mattress tufting stitches comprising an eyelet adapted to be secured in the outer sheet of a mattress, a stitch end holder consisting of a metallic connector arranged for insertion through said eyelet from the outside and having means to engage the sides of the eyelet, said eyelet and connector having cooperating means to hold the connector against rotation in the eyelet.

5. Fastening means for mattress tufting stitches comprising an eyelet adapted to be secured in the outer sheet of a mattress, a stitch end holder consisting of a metallic connector arranged for insertion through said eyelet from the outside and having means to engage the sides of the eyelet, said eyelet remaining open to ventilate the mattress after insertion of the connector, and the outer level of said end holder being substantially flush with the outer level of the eyelet in which it is mounted.
